UNITED STATES PATENT OFFICE.

JOHN R. MCGIFFERT, OF DULUTH, MINNESOTA, ASSIGNOR TO CLYDE IRON WORKS, OF DULUTH, MINNESOTA, A CORPORATION OF MAINE.

FRAME FOR TRACTOR SKIDERS AND THE LIKE.

Original application filed October 19, 1921, Serial No. 508,898. Divided and this application filed September 18, 1924. Serial No. 733,393.

In my co-pending application filed October 19, 1921, Serial No. 508,898, of which the present application is a division, I describe and claim an improved form of tractor skidder designed for use in conducting logging operations in places where it is very difficult or too expensive to extend railroad tracks into close proximity to the scene of operations. The general object of the invention is to provide a movable mounting for a skidding mechanism, such a mounting taking the form of a tractor of the continuous tread or crawler type. Further objects are to so arrange the elements of the skidding mechanism as to make the machine readily transportable on the crawler mechanism, and in this connection it has been found important so to construct the base or platform of the tractor as to prevent distortion when the machine runs over or stands upon rough or uneven ground.

To the accomplishment of such last-named and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:

Fig. 1 is a plan view of my improved tractor skidder in assembled condition, the skidding boom and the lines or cables that run thereover being omitted to avoid confusion; Fig. 2 is a broken perspective view of the platform or body of the tractor, the operating and propelling mechanism being omitted; and Fig. 3 is a cross section showing a detail of the mechanism, the plane of the section being indicated by the line 5—5, Fig. 1.

The supporting body or platform 1 of the tractor constitutes the base on which is mounted an engine 2 with a boiler 3 for supplying steam thereto, as well as a skidding boom 4, only the lower ends of the latter being shown in Fig. 1.

Said supporting body or platform, as best illustrated in the broken perspective view of Fig. 2, is composed of longitudinal beams

or girders 5, 5, joined at their respective ends by transverse girders 6, 6, on the top of which is laid, so far as necessary, a floor or deck, the latter being additionally supported where it extends beyond said longitudinal girders by means of channels 7, 7. The two longitudinal girders 5, 5, rest on two transverse girders 8, 9, the first whereof is rigidly fixed to said longitudinal girders, while the second is held against vertical or end motion but is adjustable lengthwise of said girders by means of adjusting bolts 10 and nuts 11 for a purpose presently to be explained.

Immediately adjacent to the girder 9 is a transverse channel 12, rigidly secured to the longitudinal beams or girders 5, 5; while two diagonal girders 13, 13, intersecting in the form of an X, are likewise secured to said longitudinal girders and to girders 8 and 12, said diagonal girders being flush on top with the longitudinal girders 5, 5, and on the bottom with such last mentioned transverse girders. Such diagonal or cross girders thus not only serve to unite into a strong and compact frame the deck supporting girders proper, but also the transverse girders 8 and 9 which support the traction members proper as will be subsequently described; accordingly, they prevent any torsion or twisting of the frame when operating over rough or uneven ground.

Fixed in each end of each of said cross girders 8 and 9 is a casting 15 in which is in turn rigidly fixed an axle 16. Loosely mounted on the latter are sprocket wheels 90 (not shown) that are secured to the axles by suitable collars, and around such sprocket wheels extend traction chains 19, the detailed construction of which is not of present interest, there being a variety of such chains in commercial use.

On each side of the base of the supporting body or platform, intermediately of the corresponding sprocket wheels, a series of flanged bearing wheels 20 is provided to engage the links of the traction chain passing around said sprocket wheels. Such wheels 20 thus engage the lower portion of the traction chain and are mounted in pairs on axles 21 that extend through openings 21a in longitudinal girders 22 (see Fig. 3),

such axles turning in suitable boxes 23, therefor provided. The girders 22 are, as best shown in Fig. 2, carried by pairs of transverse beams 25 that pass through the 5 diagonal or cross girders 13 and contact with the under sides of the longitudinal beams or girders 5, 5, of the main frame. The traction members are thus enabled to support said main frame directly both through 10 the medium of the sprocket wheels 17 but more especially through the roller wheels 20. By virtue of the adjustable mounting provided for the forward axles, the traction 15 chains may be tightened or loosened as occasion may require in order to retain same in easy running condition around such sprocket wheels and roller wheels. The slack in the upper portion of each traction 20 chain is taken up and such portion supported by other smaller roller wheels (not shown).

Jounaled in suitable bearings provided above the deck or platform of the main frame is a transverse shaft 30 that is adapted to be rotated by the engine 2 through suitable intermediate gearing, as need not be described in detail in the present connection. It is similarly unnecessary to describe herein the manner in which the several winding drums mounted on the platform are arranged to be operated, nor the use for which the corresponding lines or cables are designed to be put, since these form no part of the invention claimed herein. Keyed to said shaft 30 is a pinion 33 that meshes with a gear 34, keyed in turn to a second transverse shaft 35, and loosely mounted on the latter are two clutch sprockets 40, 40, such sprockets being engageable 45 with the shaft by means of friction clutches 41, 41. In the specific embodiment illustrated, these clutches are designed to be operated by means of steam jams 42, but any other form of clutch actuating device may 50 obviously be employed instead. The sprockets 40 are respectively connected by means of sprocket chains 43 with aligned sprocket wheels 44 fixed to the inside faces of the 55 respective traction sprockets 17 located at the corresponding end of the machine. By means of the driving connections thus provided, it will be seen that either traction chain 19 may be driven independently of the other or both such chains may be driven in unison. Suitable brakes are furthermore provided in conjunction with sprockets 40, whereby the machine may be held in fixed 60 position when desired, as may be necessary on a grade, and also to facilitate turning by 65 positively locking the one such sprocket and thus the corresponding traction chain against movement while the other sprocket and chain are being driven.

Other modes of applying the principle of my invention may be employed instead 65 of the one explained, change being made as regards the mechanism herein disclosed, provided the means stated by any of the following claims or the equivalent of such 70 stated means be employed.

I therefore particularly point out and distinctly claim as my invention:—

1. In a framework for a machine of the character described, the combination of spaced horizontal side members, end members connecting the same and lying in the same plane, diagonal girders extending between said side members, said girders being centrally connected, and axle supporting members mounted in spaced parallel 75 relation transversely of said side members adjacent the ends of said diagonal girders, said girders extending beneath said axle members at their points of passage beneath said side members and said girders supporting said axle members at such points. 80

2. In a framework for a machine of the character described, the combination of spaced horizontal side members, end members connecting the same and lying in the same plane, diagonal girders extending between said side members, said girders being centrally connected, and axle supporting members mounted in spaced parallel relation transversely of said side members adjacent the ends of said diagonal girders, said girders extending beneath said axle members at their points of passage beneath said side members and said girders supporting said axle members at such points, one of 90 said axle members being movable between said side members and said girders longitudinally of said framework, and means 95 adapted to position said last named axle member. 100

3. In a framework for a machine of the character described, the combination of spaced horizontal side members, end members connecting the same and lying in the same plane, diagonal girders extending between said side members intermediate said end members, said girders lying in the horizontal plane of said side members and also extending below the same, axle supporting members mounted against the bottom sides of said side members and against the ends of the downwardly extending portion of said girders, beams extending through said girders between said axle members, and longitudinally extending wheel support members attached adjacent the ends of said beams. 110 115 120

Signed by me, this 15th day of September, 1924.

JOHN R. McGIFFERT.
